P. J. HOWE,
APPARATUS FOR PIERCING TIMBER.
APPLICATION FILED APR. 28, 1920.

UNITED STATES PATENT OFFICE.

PAUL J. HOWE, OF RIDGEWOOD, NEW JERSEY.

APPARATUS FOR PIERCING TIMBER.

1,346,126.

Specification of Letters Patent.

Patented July 13, 1920.

Application filed April 28, 1920. Serial No. 377,375.

To all whom it may concern:

Be it known that I, PAUL J. HOWE, a citizen of the United States, and resident of Ridgewood, county of Bergen, and State of New Jersey, have invented certain new and useful Improvements in Apparatus for Piercing Timber, of which the following is a specification.

This invention relates to improvements in apparatus for piercing timber, and has for its general object the provision of means for rapidly and economically piercing, or forming holes or incisions in, the surface of wooden timbers, such as railway ties, piling, structural timbers, fence posts, telegraph and telephone poles, and cross-arms for telegraph and telephone poles, preparatory to treatment of the timbers with a liquid preservative such as creosote oil.

10 Other objects of the invention are to provide a piercing apparatus having a multiplicity of piercing teeth so constructed that it may be easily and rapidly shifted over the surface of a timber; to provide a piercing implement having a toothed rolling element and power-operated impact means so constructed and arranged that the impact means may be utilized to simultaneously rotate or advance the toothed element 15 along the timber and force the teeth thereon into the timber; and to provide a power-operated multi-toothed piercing element which may be readily manipulated on either sawed, hewn, or round timbers to form 20 holes or incisions over the entire surface area thereof or any desired portion of the surface of the timber.

A further object of the invention is to provide a simple and efficient power-actuated piercing device which may be readily adapted to economically practise the method of treating timber described in the patent to Goss, No. 1,252,428, dated Jan. 8, 1918.

In the accompanying drawings—

5 Figure 1 is a side elevation, partly in vertical section, of one form of apparatus embodying the invention;

Fig. 2 a fragmentary front elevation showing the type of rolling element illustrated in Fig. 1;

Figs. 3 and 4 front views, partly in section, showing two modified forms of toothed rolling elements;

Figs. 5 and 6 enlarged plan and side elevations, respectively, showing more clearly the

shape of the teeth on the rolling element illustrated in Figs. 1 and 2; and

Fig. 7 an enlarged side elevation showing the shape of the teeth formed on the sectional rolling elements illustrated in Figs. 60 3 and 4.

Referring to the drawings by numerals, 1 designates the casing or cylinder of an ordinary fluid-pressure operated hammer in which is mounted a reciprocating piston or 65 hammer head 2. The casing 1 is provided with the usual hand grip 3 at its upper end and the usual bushing, tool socket, or chuck 4 at its lower end. The usual valve 5 and operating trigger 6 therefor are provided 70 for governing the supply of fluid under pressure to the piston cylinder.

A tool shank 7 is threaded or otherwise rigidly held in the socket or chuck 4. The upper or anvil end 8 of the tool shank 7 is 75 adapted to be struck by the hammer head 2, as the head rapidly vibrates in the cylinder 1, to transmit the blow or impact of the hammer to an axle or shaft 9 supported in a yoke or fork 10 formed on the lower end 80 of the shank. The blow of the hammer head is transmitted to the axle 9 transversely of the axle.

Various forms and sizes of rolling elements, having any desired form of teeth arranged in irregular or any desired relation, may be mounted on the axle 9. In Figs. 1 and 2 a solid cylindrical roller 11 is shown, spaced at its ends from the arms of yoke 10 by washers 12. The axle 9 is held in the 90 arms of the yoke in any suitable manner, such as by cotter pins 13. The teeth 14 on roller 11 may be formed integrally therewith or may be detachably secured to the roller in any suitable manner. The teeth 95 14 may be arranged regularly or irregularly and may be of any desired form. As shown, these teeth are of diamond shape in cross-section and relatively wide at the base circumferentially of the roller and narrow longitudinally of the roller, as more clearly illustrated in Figs. 5 and 6. This form of tooth, when the machine is moved lengthwise of the timber, forms holes or incisions in the surface of the timber primarily by a 100 spreading or wedge action which opens up the surface fibers with little or no severing of the individual fibers. I have shown the teeth 14 arranged in spirally or diagonally extending rows with the teeth of each row 110

spaced short distances apart longitudinally of the rollers and the rows of teeth spaced a relatively great distance apart circumferentially of the rollers. This arrangement is advantageous for the reasons set forth in detail in the patent to Goss above referred to, since the device will form openings so located that the timber will quickly absorb a preservative in uniform quantity and to a uniform depth over its entire surface.

In Figs. 3, 4 and 7 I have shown toothed rolling elements made up of a plurality of thin steel plates or disks 15, stamped or otherwise formed with a plurality of radial teeth 16 spaced equal distances apart around the perimeter of the disks. The disks 15 are spaced apart by plain spacing disks or washers 17 and the two series of disks are detachably locked together in fixed relation by bolts 18. The toothed disks may be secured together with the teeth 16 in any desired relation. As shown, the disks are connected together with their teeth staggered to form spiral or diagonal rows of teeth having the same relation to each other as the teeth 14 on roller 11. The shape of teeth 16 may be varied as desired. As shown, these teeth are triangular in side elevation and substantially as wide at the base as the length of the inclined edges of the teeth. The teeth are beveled from one face to the other at one side to form a narrow diagonal fiber-shearing edge 19 at the point of the tooth and form beveled inclined side edges 20 which serve primarily to spread the fibers of the timber apart.

In Fig. 3 both the toothed disks 15 and the spacing disks 17 decrease in diameter toward the middle of the rolling element, thus forming a puncturing element having a concave surface. It will be understood that the solid roller 11 as well as the sectional roller may be variously shaped to adapt the rollers to efficiently act on timbers of various shape in cross-section or timbers having irregular surfaces.

In using the apparatus, the shank 7 and pneumatic hammer are preferably tilted rearwardly, as shown in Fig. 1, so that the successive impacts of the hammer head on the upper end of the shank will tend to rotate the roller and thus automatically advance the tool. The power hammer may thus be utilized to advance the tool as well as force the teeth into the timber, and, as the teeth are mounted on a rolling element the blows of the hammer serve to simultaneously force the leading teeth into the wood and withdraw the rearmost teeth from the wood. The piercing device may thus be continuously advanced with a minimum of effort on the part of the operator and it will obviously be unnecessary to bodily elevate the piercing head to withdraw the teeth and

intermittently advance and arrest the piercing head.

It will be obvious that various forms of impact devices other than fluid-pressure hammers may be employed in connection with the piercing rollers, such for example as electrically operated hammers.

What I claim is:

1. Timber piercing means comprising a rotary toothed element and means for intermittently exerting pressure on said element transversely of its axis of rotation.

2. Timber piercing means comprising a rotary element provided with a multiplicity of circumferentially and laterally spaced teeth, and means for intermittently exerting pressure on said element transversely of its axis of rotation.

3. Timber piercing means comprising a rotary element, a plurality of piercing devices carried by said element, means for rotatably supporting said element, and power-operated means for delivering blows on said supporting means.

4. Timber piercing means comprising a multiplicity of piercing devices, means for supporting said devices in laterally and circumferentially spaced relation around a common axis, and means for subjecting said supporting means to intermittent impacts.

5. Timber piercing means comprising a reciprocable impact device, means for reciprocating said device, a toothed rotary element, and means for rotatably supporting said element adapted to be struck by said impact device.

6. Timber piercing means comprising a yoke, an elongated rotary element journaled in said yoke, a multiplicity of piercing devices carried by said element spaced apart circumferentially and longitudinally of the element, and means for delivering blows on said yoke.

7. An apparatus of the class set forth comprising a rotary toothed element, and means whereby successive impacts may be transmitted to said element with the line of force extending through the axis of the element at an angle to a surface upon which the element is operating.

8. In an apparatus for piercing timber, the combination of a shank, a yoke on one end of said shank, a rotary element journaled in said yoke, a plurality of piercing devices carried by said element, and power-operated means for delivering blows in rapid succession on the other end of said shank.

9. The combination with a portable power-operated hammer having an impact head, a shank held to the lower end of said hammer with its upper end in the path of the impact head, a yoke on the lower end of said shank, a rotary element journaled in said yoke, and a plurality of rows of piercing devices carried by said element.

10. The combination with a portable power-operated hammer having an impact head, a shank held to the lower end of said hammer with its upper end in the path of the impact head, a yoke on the lower end of said shank, a rotary element journaled in said yoke, and a plurality of rows of piercing devices carried by said element, said rows of devices extending spirally around 10 said element.
11. The combination with a portable power-operated hammer having an impact head, a shank held to the lower end of said hammer with its upper end in the path of the impact head, a yoke on the lower end of said shank, a rotary element journaled in said yoke, and a plurality of rows of piercing devices carried by said element; said rows of devices extending along spiral lines 15 longitudinally of the element and the devices of each row being closer together than the distance between the different rows of devices.
12. In an apparatus for piercing timber, the combination of a shank, a yoke on one end of said shank, a rotary element journaled in said yoke, a plurality of piercing devices carried by said element, and power- 20
- operated means for delivering blows in rapid succession on the other end of said shank, 30 said element decreasing in diameter from its ends toward the center and said piercing devices being located at spaced points both longitudinally and circumferentially of the element. 35
13. Timber piercing apparatus comprising a rotary element embodying a series of toothed plates secured together with their teeth in staggered relation, means for rotatably supporting said element, and power-operated means for delivering successive blows on said supporting means in a direction transversely of the axis of said element. 40
14. Timber piercing apparatus comprising a rotary element embodying a series of toothed plates secured together with their teeth in staggered relation, means for rotatably supporting said element, and a power hammer operatively connected to simultaneously roll said element over the surface of a timber and force the teeth into and out of the timber. 45

In testimony whereof I hereunto affix my signature.

PAUL J. HOWE.
